CLOTHES BRUSH

Bertrand N. Trombley, Bloomfield Hills, Mich., assignor to Helmac Products Corporation, Flint, Mich., a corporation of Michigan

Filed Mar. 12, 1964, Ser. No. 78,968

Term of patent 14 years

(Cl. D9—2)

FIG. 1

I claim:

The ornamental design for a clothes brush, as shown.
